UNITED STATES PATENT OFFICE.

JOHN S. ROWELL AND THEODORE B. ROWELL, OF BEAVER DAM,
WISCONSIN.

SEEDER AND CULTIVATOR TOOTH.

SPECIFICATION forming part of Letters Patent No. 668,717, dated February 26, 1901.

Application filed December 24, 1900. Serial No. 40,838. (No model.)

To all whom it may concern:

Be it known that we, JOHN S. ROWELL and THEODORE B. ROWELL, citizens of the United States, and residents of Beaver Dam, in the 5 county of Dodge and State of Wisconsin, have invented certain new and useful Improvements in Seeder and Cultivator Teeth; and we do hereby declare that the following is a full, clear, and exact description thereof.

10 Our invention has for its object to provide simple, economical, and durable spring-trip seeder and cultivator teeth, said invention consisting in certain advantageous peculiarities of construction and combination of parts 15 hereinafter particularly set forth with reference to the accompanying drawings and subsequently claimed.

Figure 1 of the drawings represents a partly-sectional side elevation of a spring-trip tooth 20 in accordance with our invention, the trip of the tooth being illustrated by dotted lines in this figure; Fig. 2, a detail sectional view on the plane indicated by line 2-2 in the first figure; Fig. 3, a perspective view of an angle-bracket that partly constitutes the upper or 25 beam section of a jointed shank for the tooth-point; Fig. 4, a similar view of a portion of the point-section of said shank, and Fig. 5 a like view of a toggle employed in connection 30 with the shank-sections and provided with a set-screw adjustable against one of said shank-sections to regulate tension of a compression-spring on a rod shackled to the toggle.

Referring by letter to the drawings, A indicates each of a pair of flat metal bars that 35 are set edgewise and connected together to form a draft-beam. Bolted between the beam-bars at their rear ends is a horizontal arm B of an angle-bracket having a depending vertical arm C, provided with an apertured enlargement b near its intersection with the former arm, said angle-bracket being preferably malleable iron and made with upper vertical and horizontal flanges c d, abutting the 45 rear extremities and lower edges of the beam-bars A aforesaid. The angle-bracket is also made with a rearwardly-extending upper lug e, to which the upper ends of a pair of parallel links D are pivotally connected, the 50 lower ends of these links being likewise connected to the upper extremity of a forked

block E, that is also preferably malleable iron and made with an enlargement f, having a threaded aperture engaged by a set-screw F, said links and block constituting a toggle. 55

The arm B of the angle-bracket constitutes the upper section of a shank for a tooth-point G, the other section H of the shank being in bolt-and-nut connection with the point and pivotally engaged at the upper end with the 60 forked lower portion of said bracket-arm. The lower shank-section is provided with an upper lug g, that has pivotal engagement with the forked lower portion of block E, constituting part of the above-described toggle, the 65 set-screw F of said toggle being impinged against the rear edge of the upper or beam section of the shank. By providing lug g with a plurality of apertures, as is herein shown, the normal set of the tooth-point may 70 be varied.

A rod I is shown as having an end eye h engaged by a bolt i, that extends through apertures made in links D, above specified, and this rod in shackle connection with the aforesaid toggle has play in the aperture with which the enlargement b of arm B of the angle-bracket or beam-section of the jointed point-shank is provided. A spiral spring J is arranged on the rod to be compressed between the aforesaid arm and a washer K, a radial branch j of this washer being extended up between the beam-bars A, set forth in the foregoing. The forward end of rod I is screw-threaded and has a nut L run thereon against 85 the aforesaid washer, the normal tension of spring J being regulated by adjustment of set-screw F, hereinbefore specified.

When the tooth-point G meets obstructions of more than ordinary resistance in its path, 90 it will yield with the toggle-joint in a rearward direction, there being proportionate compression of spring J, this operation being illustrated by dotted lines in Fig. 1. The obstruction having been passed, there will be expansion of spring J and automatic return of the tooth-point and toggle-joint to their normal positions. Incidental to an automatic trip and recovery of the tooth-point the radial branch j of washer K will have play between the beam-arms A to clear away possible accumulations 95 of trash, such as grass and weeds. 100

From the foregoing it will be particularly observed that rod I and spring J are close under the draft-beam out of the way and directly over the center of tooth-point G, this being 5 an advantageous arrangement.

While we have shown a preferred construction and arrangement of parts, the same may be more or less varied in practice without departure from our invention in its broadest 10 terms.

Having thus described our invention, what we claim as new, and desire to secure by Letters Patent, is—

1. The combination of a draft-beam, a jointed 15 point-shank in depending rigid connection with the beam, a rear toggle connecting the point-shank sections, a rod that being shackled to the toggle extends through an aperture in the upper one of said shank-sections, and a 20 spiral spring held on the rod to have its rear end abut said upper shank-section.

2. The combination of a draft-beam, a jointed 25 point-shank in depending rigid connection with the beam, a rear toggle connecting the point-shank sections, a rod that being shackled to the toggle extends through an aperture in the upper shank-section, a spiral spring held 30 on the rod to have its rear end abut said upper shank-section, and means for regulating normal tension of the spring.

3. The combination of a draft-beam, a jointed 35 point-shank in depending rigid connection with the beam, a rear toggle connecting the point-shank sections, a rod that being shackled to the toggle extends through an aperture in the upper shank-section, a spiral spring held 40 on the rod to abut said upper shank-section, and a set-screw adjustable in a section of the toggle against the aforesaid upper shank-section.

4. The combination of a draft-beam comprising 45 a pair of flat bars set edgewise, an angle-bracket having a horizontal arm made fast between the beam-bars and a depending arm constituting part of a jointed point-shank, a rear toggle in connection with rear lugs of

the bracket and lower point-shank section, a set-screw adjustable in a toggle-section against the depending arm of the bracket, a rod that being in shackle connection with the 50 toggle extends through an aperture in said depending bracket-arm, and a spiral spring held on the rod to abut the aforesaid depending bracket-arm.

5. The combination of a draft-beam comprising 55 a pair of flat bars set edgewise, a jointed point-shank the upper section of which is a depending arm of an angle-bracket made fast between the beam-bars, a rear toggle connecting the point-shank sections, a rod that 60 being shackled to the toggle extends through an aperture in said upper point-shank section, a washer facing a nut on the forward end of the rod and having a radial branch extending up between said beam-bars, and a spiral 65 spring arranged intermediate of the washer and aforesaid upper point-shank section.

6. The combination of a draft-beam comprising 70 a pair of flat bars set edgewise, a jointed point-shank the upper section of which is a depending arm of an angle-bracket made fast between the beam-bars, a rear toggle connecting the point-shank sections, a rod that 75 being shackled to the toggle extends through an aperture in said upper point-shank section, a washer facing a nut on the forward end of the rod and having a radial branch extending up between said beam-bars, a spring arranged intermediate of the washer and aforesaid upper point-shank section, and means 80 for adjusting said toggle to regulate normal tension of the spring.

In testimony that we claim the foregoing we have hereunto set our hands, at Beaver Dam, in the county of Dodge and State of Wisconsin, in the presence of two witnesses.

JOHN S. ROWELL.
THEODORE B. ROWELL.
